(57) **CLAIM**

The ornamental design for a fluid transfer connector, substantially as shown and described.

DESCRIPTION

FIG. 1 is a first perspective view of a fluid transfer connector according to an embodiment of the design.

FIG. 2 is a second perspective view of the fluid transfer connector shown in FIG. 1.

FIG. 3 is a front view of the fluid transfer connector shown in FIG. 1, the rear view and left and right side views being substantially identical to the front view.

FIG. 4 is a cross-sectional view of the fluid transfer connector shown in FIG. 1 taken along line 4-4 of FIG. 3.

FIG. 5 is a top view of the fluid transfer connector shown in FIG. 1; and,

FIG. 6 is a bottom view of the fluid transfer connector shown in FIG. 1.
